UNITED STATES PATENT OFFICE.

RAY E. COON, OF YATES, NEW YORK.

WALL-BRACKET.

1,090,687.

Specification of Letters Patent. Patented Mar. 17, 1914.

Application filed October 3, 1913. Serial No. 793,181.

To all whom it may concern:

Be it known that I, RAY E. COON, a citizen of the United States, and residing at town of Yates, in the county of Orleans and State of New York, have invented certain new and useful Improvements in Wall-Brackets, of which the following is a specification.

This invention relates to improvements in wall brackets and more especially to a hinged bracket for a folding wall table.

An object of the invention is the provision of a bracket adapted for use in pairs having a novel form of hinged and linked strut operating with the folding of the bracket.

A further object of the device is to provide a bracket support for a table by which the table is automatically locked in its open horizontal position upon being elevated to such position.

A still further object is to provide brackets that will substantially inclose the folding strut within the leaves of the hinge members when the bracket is closed.

With these general objects in view and others that will appear as the nature of the invention is better understood, the same consists in the novel combination and arrangement of parts hereinafter fully described, illustrated in the accompanying drawings, and pointed out in the appended claims.

In the drawings forming a part of this application and in which like reference characters designate corresponding parts throughout the several views: Figure 1 is a perspective view of one of the improved brackets. Fig. 2 is a front view of a table wall in opened position illustrating the employment of two brackets supporting the same. Fig. 3 is a side view of the structure shown in Fig. 2. Fig. 4 is a transverse sectional view through the bracket in its closed position, and, Figs. 5 and 6 are detail views of the lock hinge for the strut in locked and unlocked positions respectively.

Referring in detail to the drawings, it may be first noted that the hinged automatically locking bracket now devised is primarily designed to support a shelf or wall table 10, upon a support or wall 11, any desired number of brackets being employed for such means, such as two, as disclosed in Fig. 2. The leaves 12 and 13 of the bracket are formed of angle metal and secured together by a hinge such as 14, the attach-

ment of the bracket leaves to the wall and table being accomplished in any desired and well-known manner. The said angular leaves having one of their sides thus attached to the wall and table respectively, their other sides 15 must outwardly project from such supporting members and said sides 15 are oppositely positioned and when the bracket is closed, form an elongated inclosure substantially rectangular in cross-section as shown in Fig. 4. A locking strut or brace is pivoted between said projecting sides 15 of the bracket leaves, the said strut consisting of an upper member 16 pivoted as at 17 to the upper leaf and also includes the lower member 18 hinged to the leaf 12 as at 19. The said upper strut member 16 is provided at a point slightly removed from its free end with a projecting headed pin 20 slidably positioned in the slot 21 adjacent the free end of the lower member 18 and permanently retained in said slot by means of its head. Said upper member being angular in cross-section, the side 70 thereof which is pivoted to the bracket leaf has the said pin 20 mounted thereon while the other side of said strut member has its free end provided with an inwardly projecting notch or slot 22. The lower strut member 18 is formed of a metallic U-shaped bar having its opposite sides cut-away obliquely from the opposite ends of the strut. The headed projecting stud 24 is positioned adjacent the free end of the lower 80 member 18 and upon the base of said member and is adapted to slidably receive the said slot 22 beneath the head of said stud.

The construction of the strut, it will be apparent from the drawings, is such that 95 the same will hinge medially as illustrated in Fig. 6 upon removing the notch 22 from the stud 24, its members hinging upon the stud 20 sliding longitudinally within the slot 21 for the purpose of releasing the notch 22 from the stud 24 and whereupon the bracket and its supported member will readily close. From the closed position, it is only necessary to elevate the upper leaf 13 of the bracket or the table 10 to its uppermost point when the struts will assume their continuous position and by reason of the weight of the supported member and upper strut member, the notch 22 will engage with the stud 24 and lock the bracket as well as 110 its table in the open position. The form of the strut members is not only material to the

perfect operation of the device but also as to its simplicity and reduces the cost of manufacture.

While the forms of the invention herein shown and described are what are believed to be preferable embodiments thereof, it is nevertheless to be understood that minor changes may be made in the form, proportion and details of construction without departing from the spirit and scope of the invention as set forth in the appended claims.

Having thus fully described my invention, and in what manner the same is designed for use, what I claim as new and desire to secure by Letters Patent of the United States is:—

1. A bracket comprising angular leaves hinged together, one angular and one U-shaped strut member, one of each being pivoted to the projecting side of said leaves and an interlocking slidable connection between said strut members.

2. A bracket comprising angular leaves, an angle metal strut member pivoted to the projecting side of one of said leaves and having a notch in its free end, a U-shaped strut member pivoted at one end through all of said leaves and having a slot adjacent its free end, a headed stud carried upon said upper member and slidably secured in said slot, and a stud upon the free end of said lower strut member adapted for removable engagement with said notch.

3. A device of the class described compris-

ing two angle metal leaves hinged together, the projecting sides of said leaves being oppositely positioned, an angle metal strut member pivoted to the projecting side of said upper leaf, a channel metal strut member pivoted to the opposite projecting side of said other leaf, and a sliding interlocked hinge between said strut members.

4. A device of the class described comprising two angle metal leaves hinged together, the projecting sides of said leaves being oppositely positioned, an angle metal strut member pivoted to the projecting side of said upper leaf, a channel metal strut member pivoted to the opposite projecting side of said other leaf, a sliding interlocked hinge between said strut members, said upper strut member provided with a stud upon one side thereof and a notch at the end of its other side, said lower strut member provided with a slot slidably-mounted upon said stud and also having a headed stud upon another one of its sides adapted for the reception of said notch beneath the head thereof upon the open position of said strut and bracket.

In testimony whereof I affix my signature 60 in presence of two witnesses.

RAY E. COON.
